DESIGN FOR A TEMPLATE

Gordon E. Kardux, Burbank, Calif.

Application February 21, 1944, Serial No. 112,652

Term of patent 7 years

(Cl. D52—1)

To all whom it may concern:

Be it known that I, Gordon E. Kardux, a citizen of the United States, residing at Burbank, in the county of Los Angeles and State of California, have invented a new, original, and ornamental Design for a Template, of which the following is a specification, reference being had to the accompanying drawing, forming part thereof.

Fig. 1 is a top plan view of a template, showing my new design.

Fig. 2 is a sectional view taken on line 2—2 of Fig. 1.

I claim:

The ornamental design for a template, substantially as shown.

GORDON E. KARDUX.
